Primary Examiner — Eric Goodman(74) *Attorney, Agent, or Firm* — Sheridan Ross P.C.**CLAIM**

The ornamental design for a bathtub overflow pipe, as shown and described.

DESCRIPTION

FIG. 1 is a perspective view of the bathtub overflow pipe showing the new design;

FIG. 2 is a front elevation view thereof;

FIG. 3 is a right elevation view thereof, the left elevation view being a mirror image thereof;

FIG. 4 is a rear elevation view thereof;

FIG. 5 is a top plan view thereof; and,

FIG. 6 is a bottom plan view thereof.

The broken lines in the figures show environment for illustrative purposes only and forms no part of the claimed design.
